UNITED STATES PATENT OFFICE

ANDY BOCHNAK, OF BOBTOWN, PENNSYLVANIA

REPEATING RIFLE

Application filed November 15, 1929. Serial No. 407,475.

This invention relates to an improved repeating rifle and has as one of its objects to provide a repeating rifle by which a greater number of cartridges may be successively fired than by the use of the ordinary repeating rifle embodying the usual shiftable cartridge carrier.

The rifle embodying the invention is provided with a cartridge cylinder which is 10 rotatably mounted upon the stock of the rifle so that the peripheral portion of the barrel may be intermittently moved with a step-by-step movement past the firing pin and hammer, and another object of the invention is 15 to provide a barrel embodying a number of shell chambers so arranged and constructed that they may be securely locked in place upon the body of the barrel and the shells which are employed, located in the respective chambers, so that notwithstanding the 20 fact that the cap ends of the shells are exposed at the rear side of the barrel, there is no likelihood of the shells being accidentally displaced from the chambers of the barrel, 25 and in this connection the invention also contemplates a novel means whereby the shell chambers may be readily released when it is desired to cleanse the same.

Another object of the invention is to provide 30 a novel means whereby intermittent rotary motion will be automatically imparted to the shell barrel each time the trigger of the rifle is pulled, so that by merely pulling the trigger, a successive number of times, as 35 many shells as desired may be successively discharged in rapid order.

Another object of the invention is to provide 40 a novel firing pin for the rifle which pin may be readily dismounted and a new pin substituted therefor without necessitating any separation of the parts of the rifle or a 45 dismounting of the same, except for the removal of the carrier for the pin.

Another object of the invention is to provide 50 a novel means for locking the cartridge cylinder in its successive positions of adjustment, so that each cartridge will, in order, be present in direct axial alinement with the barrel of the rifle, preparatory to being discharged.

This invention also consists in certain other features of construction and in the arrangement of the several parts, to be hereinafter fully described, illustrated in the accompanying drawings and specifically pointed out in 55 the appended claims.

In describing my invention in detail, reference will be had to the accompanying drawings wherein like characters denote like or corresponding parts throughout the several views, and in which:

Figure 1 is a view in side elevation of a rifle constructed in accordance with the present invention.

Figure 2 is a front elevation of the rifle. 65

Figure 3 is a vertical longitudinal sectional view taken substantially on the line 3—3 of Figure 2 looking in the direction indicated by the arrows.

Figure 4 is a view in rear elevation of the 70 cartridge barrel removed from the rifle.

Figure 5 is a view in side elevation of one of the cartridge chambers of the cartridge storing barrel.

Figure 6 is a view in top plan illustrating 75 the said chamber.

Figure 7 is a view similar to Figure 6 illustrating a form of chamber which is arranged alternately with the chambers shown in Figures 5 and 6. 80

Figure 8 is a detail plan view of an element which is provided for imparting rotary motion, intermittently, to the cartridge storing barrel.

Figure 9 is a plan view illustrating certain coating elements by which the element shown in Figure 8 is actuated. 85

Figure 10 is a top plan view of a ratchet also constituting a part of said means.

Figure 11 is a view in side elevation of 90 the ratchet.

Figure 12 is a plan view of the locking means for holding the barrel in its positions of rotative movement.

Figure 13 is a detail view of a part of the trigger and hammer mechanism of the rifle. 95

In the drawings the stock of the rifle is indicated by the numeral 1 and the usual barrel by the numeral 2 and the said stock includes a body member which may be cast or 100

machined, and which is indicated in general by the numeral 3. At its forward end, the stock body 3 is exteriorly of slightly greater diameter than the butt end of the barrel 1 and the said body is formed at its said end with a bore 4 which receives the exteriorly reduced body end of the barrel, this end of the barrel being held in place by screws 5.

Preferably the bore 4 is reduced at its inner end as indicated by the numeral 6 so as to accommodate the further reduced body end portion 7 of the barrel, this end being flush with the rear side of the reduced portion 6. The stock body 3 is further formed with depending front and rear portions indicated by the numerals 8 and 9 respectively, and a spindle 10 is fitted through an opening in the portion 8 and threaded at its rear end in an opening in the portion 9. The cartridge storing barrel is rotatably mounted upon a spindle 10 and the upper portion of the barrel rotates in a recess 11 formed in the upper portion of the member 3.

The cartridge supporting and storing barrel is indicated in general by the numeral 13 and the same comprises an annular rim 14 and short spokes 15 which radiate from the sleeve like hub 16 which rotatably fits the spindle 10. A circumferential groove 17 is formed in the rim 14 of the barrel and the side walls of this groove are beveled so as to converge in the direction of the periphery of the rim as indicated by the numeral 18, and, as clearly shown in Figure 3 of the drawings, the forward side wall of the groove 17 is likewise beveled as indicated by the numeral 19. This groove is continuous except that, at equi-distantly spaced points in the circumference of the barrel rim, short grooves 20 are formed which open through the rear side of the barrel rim and communicate at their inner ends with the groove 17.

These grooves 20 are of a width slightly greater than the diameter of one of the cartridge chambers, heretofore referred to, and the structure and arrangement of these chambers will now be described.

The cartridge chambers, referred to, are shown clearly in Figures 5, 6 and 7 of the drawings, and two kinds of chambers are employed and are alternately arranged. One of these chambers, illustrated in Figures 5 and 6 of the drawings and indicated in general by the numeral 21 is of cylindrical tubular form and interiorly of a diameter to accommodate a cartridge 22 of the usual type, which cartridge is preferably provided near its butt end with a circumscribing groove 23, which is pressed in the shell thereof. Each of the chambers is formed upon what will constitute its inner side when the chambers are arranged about the barrel 13, with a boss 24 having beveled ends 25 and beveled sides 26 and this boss is of cross sectional dimensions to adapt it to fit

slidably through the groove 20 when the chamber 21 is slid into the groove 17. The cartridge chamber shown in Figure 7 is identical with the chamber shown in Figures 5 and 6 so far as the latter chamber has been described, except that the rear end of the boss 24 thereof is not beveled, but in a plane at right angles to the axis of the chamber as indicated by the numeral 27. Therefore, this plane or straight end portion of the boss 24 of the said chamber shown in Figure 7 is adapted to seat in and fill the respective groove 20 which constitutes an extension of the groove 17.

Each of the chambers 21 shown in Figures 5 and 6, is formed, near its rear end, with a slot 28 extending a short distance about the circumference of the chamber and a similar slot 29 is formed in that side of the chamber shown in Figure 7 which is presented toward the side of the chamber shown in Figure 5, in the assembled alternate arrangement of the two chambers, in which the slot 28 is formed, so that the slots 28 and 29 of the two forms of chambers, are located opposite each other. Each of the chambers 21, shown in Figures 5 and 6 of the drawings, has mounted thereon a locking means which comprises a flat sided lever 30 pivotally mounted as at 31, upon the same side of the chamber as that in which the slot 28 is formed, and this lever is provided at its rear end with a flat sided lock head 32 which is disposed in a plane at right angles to the plane of the lever and which therefore projects beyond the opposite sides of the lever at its said rear end so that its projecting edge portions will engage in the slots 28 and 29 in the two chambers 21 and 21' when the lever is in the position shown in Figure 5 of the drawings, and preferably the head 32 will be provided with a cross piece 33, at its upper edge, the ends of which may, in this position of the lever, rest upon the outer sides of the chambers 21 and 21'. The said side edges of the head 32 of each locking lever 31 likewise engage in the grooves 23 formed in the shells of the cartridges in the chambers 21 upon which the lever is mounted and the chamber 21' next adjacent the said chamber 21, so that not only are the chambers 21 held against the outward sliding movement of their bosses 24 through the grooves 20, but likewise the cartridges in the chambers are prevented from displacement. Each lever 34 has a finger piece 35 at its forward end, and a tension spring 36 is connected to an ear 37 provided at the lower edge of the lever below and slightly forwardly of the pivot 31 and connected at its other end to the barrel 21 near the forward end thereof so that the lever 30 is normally held in the locking position shown in Figure 5, it being understood, however, that by depressing the forward end 35 of each lever, 130

the discharged shells may be removed from the chambers and likewise the chamber 21' may be removed from the cartridge barrel 13 and the adjacent chamber 21 shifted to bring its bosses 24 opposite the groove 20, whereupon it too may be removed from the barrel.

The firing pin of the rifle is indicated by the numeral 38 and the same has its diameter 10 reduced throughout its forward portion so as to provide a shoulder 39 against which bears one end of a compression spring 40 which is mounted in the bore of a bushing 41 threaded into a socket in the rear end of 15 the stock 3, the other end of the spring bearing against the inner end of said bore and the bore being reduced at its inner end so as to accommodate the similar end of the firing pin, the pin being pointed at its extreme forward end as at 42 and projecting at its rear end beyond the said bushing 41.

This construction of firing pin and the manner in which it is mounted provides for ready removal of the bushing and removal of 25 the pin in the event it is desired to replace the pin.

The hammer of the rifle is indicated in general by the numeral 43 and is provided at its lower end with a head 44 which is pivotally mounted upon a cross pin 45 in a recess 46 in the rear portion of the stock, the upper end of the hammer being provided with a finger piece 47 whereby the hammer may be swung back about its pivot against the tension of a tension spring 48 which is connected at its upper end to a pin 49 within the recess 46 and at its lower end to an ear 50 formed at the rear edge of the head 44. The head of the hammer is indicated by the numeral 51, and, in the retracted position of the hammer, occupies substantially the position shown in Figure 3 of the drawing with respect to the firing pin 38. The hammer is provided with an abutment lug 52 at the forward side of its head 44, and the numeral 53 indicates a rack bar which is slidably mounted in one side of the recess 46 and is provided at its rear end with a laterally projecting lug 54, which is, in one position of the rack bar, located below the abutment lug 52 upon the hammer so as to hold the hammer in its retracted position as shown in Figure 3. This abutment lug 54 also constitutes a part engageable by a finger 55 extending forwardly from the trigger of the rifle which trigger is indicated by the numeral 56, and is pivotally mounted, as at 57, in the lower portion of the recess 56, the finger piece of the trigger being indicated by the numeral 58 and the trigger guard by the numeral 59. The head 44 of the hammer 43 is formed in its lower side with a notch indicated by the numeral 60, and a pawl 61 is pivotally mounted as at 62 upon the head of the trigger 56, and is yieldably held by a spring 63, in en-

gagement at its toothed end 64 with the periphery of the head 44 so as to be engageable in the notch 60 when the parts are in the position shown in Figures 3 and 13 of the drawings.

The rack bar 53 is provided with an upwardly offset rearward extension indicated by the numeral 65, and this extension slides in a groove 66 formed in one side wall of the recess 46, and the said rack 53 meshes with a pinion 67 which is rotatable about a spindle 68 mounted vertically in a forward extension of the recess 46, a ratchet 69 being fixed with respect to the pinion 67, for rotation therewith, and a pawl 70 is mounted 70 upon the pinion 67 at the upper side thereof and yieldably held, by a spring 71, in engagement with the ratchet 69. At its upper side the ratchet is provided with spaced lugs 72 radial to the axis of the ratchet and these 75 lugs engage in sockets 73 formed in the under side of a pin wheel 74 which has a series of pins or studs 75 projecting from its periphery to engage in sockets 76 formed in the rear face of the rim of the drum 13. At this point it 80 will be evident and particularly by reference to Figure 3 that when the trigger is pulled, the rack bar 53 will be shifted forwardly thus first cocking the hammer 47 from its neutral position shown in Figure 3, and then releasing the hammer by disengagement of the pawl 61 from the notch 60, and as the lug 54 moves forwardly, the pinion 67 will be rotated as also the ratchet 69 and the pin wheel 74 will likewise be rotated so as to rotate the 85 cartridge supporting drum a distance of one of the cartridge housing chambers 21 or 21', as the case may be and bring this chamber and the cartridge therein into position for impact of the cartridge cap by the firing pin, 90 when the hammer is released.

In order to prevent any rotative displacement of the drum 13 after it has been rotated one step in its rotative movement, as above described, means is provided which will now 95 be described.

The means referred to comprises a detent lever 77 which is pivotally mounted as at 78 within the recess 46 and extends through the forward extension of the recess, and with its 100 end located within the bounds of the rim 14 of the cartridge carrying drum, a tooth 79 being carried at the end of the detent lever and engageable successively in an annular series of sockets 80 formed in the inner side 105 of the said rim. A tension spring 81 is connected at one point to a fixed element upon the side wall of the recess 46 and at its outer end to the upper side of the detent lever 77 slightly rearwardly of its pivot 78 and the 110 detent lever is provided in rear of its pivot with a finger, indicated by the numeral 82 and the end of this finger rests upon the extension 52 of the hammer 43, and, when the 115 hammer is cocked this extension 52 riding 120

upwardly will effect rocking movement of the detent lever against the tension of the spring 81 to retract the tooth 79 from the socket 80 in which it is at that time engaged to release the cartridge drum for rotation to bring a fresh cartridge into position opposite the firing pin, next, the rack bar 53 is retracted and the pinion 67 is reversely rotated to effect rotation, for a part of a revolution of the pin wheel 74 to bring in one of the pins 75 upon said wheel, into engagement with the socket 76, next in order in the series.

What I claim is:—

1. In a repeating rifle, a stock, a firing barrel extending therefrom, a cartridge storing barrel rotatably mounted upon the stock, means upon the periphery of the barrel for supporting an annular series of cartridges for presentation, successively, to the firing end of the barrel, a firing pin upon the stock, a hammer upon the stock for coaction with the firing pin, a trigger, and means actuated, automatically, upon pulling of the trigger, to first advance the cartridge storing barrel one step in its rotative movement to bring a cartridge into alignment with the stock barrel and with the firing pin, and to cock the hammer and then release the same for impact with the firing pin, upon further pulling of the trigger, the means for automatically advancing the cartridge storing barrel comprising a rack member slidably actuated through initial pulling of the trigger, a gear engaged by the said rack, and a rotatable member actuated by rotation of the gear and having a series of studs for engagement in sockets in the barrel.

2. In a repeating rifle, a stock, a firing barrel extending therefrom, a cartridge storing barrel rotatably mounted upon the stock, means upon the periphery of the barrel for supporting an annular series of cartridges for presentation, successively, to the firing end of the barrel, a firing pin upon the stock, a hammer upon the stock for coaction with the firing pin, a trigger, and means actuated, automatically, upon pulling of the trigger, to first advance the cartridge storing barrel one step in its rotative movement to bring a cartridge into alignment with the stock barrel and with the firing pin, and to cock the hammer and then release the same for impact with the firing pin, upon further pulling of the trigger, the means for releasing the hammer comprising a rack member slidably actuated through pulling of the trigger, an abutment lug upon the rack, and a finger upon the hammer resting upon the lug, the movement of the rack, to position to complete actuation of the cartridge storing barrel, serving to move the lug out of engagement with said finger, whereby to permit of actuation of the hammer.

3. In a repeating rifle, a stock, a firing barrel extending therefrom, a cartridge storing

barrel rotatably mounted upon the stock, means upon the periphery of the barrel for supporting an annular series of cartridges for presentation, successively, to the firing end of the barrel, a firing pin upon the stock, a hammer upon the stock for coaction with the firing pin, a trigger, and means actuated, automatically, upon pulling of the trigger, to first advance the cartridge storing barrel one step in its rotative movement to bring a cartridge into alignment with the stock barrel and with the firing pin, and to cock the hammer and then release the same for impact with the firing pin, upon further pulling of the trigger, the means for releasing the hammer comprising a rack member slidably actuated through pulling of the trigger, an abutment lug upon the rack, and a finger upon the hammer resting upon the lug, the movement of the rack to position to complete actuation of the cartridge storing barrel, serving to move the lug out of engagement with said finger whereby to permit of actuation of the hammer, a spring connected with the stock and with the hammer and yieldably urging the hammer to firing position, and a spring connected to the stock and to the trigger yieldably urging the trigger to non-firing position.

4. In a repeating rifle, a stock, a firing barrel extending therefrom, a cartridge storing barrel rotatably mounted upon the stock, means upon the periphery of the barrel for supporting an annular series of cartridges for presentation, successively, to the firing end of the barrel, a firing pin upon the stock, a hammer pivotally mounted upon the stock, the said cartridge storing barrel being provided in its rear side with an annular series of sockets, a disk rotatable in the barrel and provided with a peripheral series of studs engageable in said sockets in the rotation of the disk, a detent lever mounted for pivotal movement and having a portion for locking engagement with the said cartridge storing barrel for holding the barrel in positions of rotative adjustment, a spring yieldably urging the lever to engaging position, a finger upon the hammer engaged by the lever at the other side of its pivot to effect movement of the lever to release the barrel at the moment the hammer is cocked and released, a slideable rack upon the barrel, gear connection between the rack and the said disk for effecting rotative movement of the said disk upon movement of the rack, a spring yieldably urging the rack to retracted position, a finger upon the trigger, the rack having a detent lug, a finger upon the hammer engaging the said lug in the retracted position of the rack, the said hammer having a pivoted head, the edge of which is concentric to the pivot for the hammer and provided with a notch, and a pawl upon the trigger yieldably held in engagement with the said edge of the

pivoted head of the hammer and engageable in the notch in the retracted position of the hammer.

5. A rotary cartridge carrier for repeating rifles comprising a barrel having a circumferential groove in its periphery, the walls of said groove being inwardly beveled, and a plurality of cartridge chambers provided with beveled bosses seating in said groove and 10 extending in an annular series about the barrel.

6. A rotary cartridge carrier for repeating rifles comprising a barrel having a circumferential groove in its periphery, the walls of said groove being inwardly beveled, one wall of the groove having inwardly widened recesses formed at intervals therein, and a plurality of cartridge chambers provided with bosses, the bosses of certain of said chambers being 15 beveled at their ends to engage the walls of the groove and also beveled at their sides to be slidably engaged through the recesses in the said wall and thus introduced into the groove, the other chambers being arranged 20 alternately with respect to the first mentioned chambers, and each having the sides of its boss beveled and the forward end of its boss beveled, the rear ends of the bosses of the said alternate chambers being straight whereby to 25 fit within and fill the said recesses in the said wall of the groove, and a locking member upon each of the first mentioned chambers engageable with a part of the next adjacent second mentioned chamber for holding the 30 chambers against relative longitudinal displacement, whereby the engagement of the rear beveled side of the boss of each of the first mentioned chambers with the respective wall of the groove in the barrel will prevent 35 rearward displacement of the chamber with respect to the barrel and the engagement of the locking member upon said first mentioned chamber, with the second mentioned chamber, and will prevent movement of the second mentioned chamber rearwardly by the 40 sliding of its boss through the respective recess in the wall of the groove.

7. A rotary cartridge carrier for repeating rifles comprising a barrel having a circumferential groove in its periphery, the walls of said groove being inwardly beveled, one wall of the groove having inwardly widened recesses, formed at intervals therein, and a plurality of cartridge chambers provided with 50 bosses, the bosses of certain of said chambers being beveled at their ends to engage the walls of the groove and also beveled at their sides to be slidably engaged through the recesses in the said wall and thus introduced 55 into the groove, the other chambers being arranged alternately with respect to the first mentioned chambers, and each having the sides of its boss beveled and the forward end of its boss beveled, the rear ends of the bosses 60 of the alternate chambers being straight 65

whereby to fit within and fill the said recesses in the said wall of the groove, and a locking member upon each of the first mentioned chambers engageable with a part of the next adjacent second mentioned chamber for holding the chambers against relative longitudinal displacement, whereby the engagement of the rear beveled side of the boss of each of the first mentioned chambers with the respective wall of the groove in the barrel will 70 prevent rearward displacement of the chamber with respect to the barrel, and the engagement of the locking member upon said first mentioned chamber, with the second mentioned chamber, and will prevent movement of the second mentioned chamber rearwardly by the sliding of its boss through the respective recess in the wall of the groove, the locking member comprising a lever pivotally mounted upon the side of each of the first mentioned chambers which is presented toward the respective adjacent one of the second mentioned chambers, a transverse head at one end of the lever having parallel marginal portions, the relatively adjacent barrels having slots in their opposing sides in which said marginal portions of the head are 75 engageable to provide for locking of the member with respect to each other, and a spring yieldably holding each lever in locking position.

In testimony whereof I affix my signature.
ANDY BOCHNAK.
